RAILWAY TRAFFIC CONTROLLING APPARATUS

Charles M. Hursh, Downers Grove, Ill., assignor to Westinghouse Air Brake Company, Wilmerding, Pa., a corporation of Pennsylvania

Application June 22, 1953, Serial No. 363,164

6 Claims. (Cl. 246—22)

My invention relates to railway traffic controlling apparatus. More particularly, my invention relates to apparatus of the type which is known as traffic locking apparatus, by means of which, traffic governing devices, such for example as signals for any given stretch of railway track, are in part manually controllable for governing traffic movements in both directions, and by means of which, traffic governing devices, after being controlled for governing traffic movements in one direction or the other over a stretch of railway track, cannot be controlled for governing traffic movements in the opposite direction while the stretch of track is occupied by a train, or while a traffic governing device, such for example as a signal, is controlled for authorizing a train to proceed in the former direction onto the stretch of track.

One form of traffic locking apparatus which has been used requires joint action by persons at two different control stations for manually controlling traffic movements in both directions over a stretch of railway track. Each of the two control stations may be provided with an interlocking machine, and each of the interlocking machines may be equipped with a traffic lever which is mechanically interlocked with a signal lever which controls a signal for governing traffic movements on to the corresponding end of the stretch of railway track.

In the particular form of apparatus shown embodying my invention, however, an improved traffic control system manually controllable from only one control station is employed, in which polar control relays, and neutral line relays one for each polar control relay are energized in series by current of one polarity or the other in a circuit which includes a contact of each of a plurality of track relays and other traffic controlled relays for a corresponding stretch of railway track and which also includes contacts of two time locking stick relays, one for each end of the stretch of track, controlled in conjunction with a signal for governing traffic movements entering the stretch of track at the corresponding end of the stretch of track. Each of the polar control relays is of the polar stick type having polar contacts which, when the corresponding relay becomes deenergized, remain closed in the normal or the reverse position to which they were last operated in response to current of normal or reverse polarity, respectively.

Two track circuits, of the coded type, normally deenergized, one for each direction of traffic movements, are shown provided for each track section between signals, adjacent opposite ends of the stretch of track, which govern traffic movements off of the stretch of track. It is, however, not necessary that the track circuits shall be of the particular type shown. The track circuits for a given direction of traffic movements are set up by contacts of the polar control relays when closed in a given or normal position in response to energization of the polar control relays by current of a given normal polarity, and by back contacts of the corresponding neutral line relays, and the track circuits for the opposite direction of traffic movements are set up by contacts of the polar control relays

when closed in the opposite or reverse position in response to energization of the polar control relays by current of the opposite or reverse polarity, and by back contacts of the corresponding neutral line relays.

5 It is believed to be obvious that, with this traffic locking system, the neutral line relays cannot be used alone for controlling block indication devices to show traffic conditions on the different track sections or blocks in the associated stretch of track.

10 An object of my invention, therefore, is the provision of means which will control block indication devices to show correctly the condition of track occupancy of the various blocks.

15 Another object of my invention is the provision of means for lighting a signal for the given stretch of railway track only when a given portion of the track in the rear of the signal is occupied by a train.

20 A feature of my invention for accomplishing these objects is the use of traffic direction stick relays controlled to be normally energized but to become deenergized in response to control of corresponding signals by the traffic locking circuit arrangement to display proceed indications for a corresponding direction of traffic movements over the associated stretch of railway track.

25 A further feature of my invention is the provision of indication control means controlled to be normally energized and also to be energized when a signal is controlled to display a proceed indication while a corresponding traffic direction stick relay is deenergized, but to become deenergized when the same signal is controlled by a train to display a stop indication.

30 I shall describe one form of apparatus embodying my invention, and shall then point out the novel features thereof in claims.

35 The accompanying drawings, Figs. 1a, 1b, and 1c, when placed end to end, in the order named, with Fig. 1a on the left, constitute a diagrammatic view showing one form of apparatus embodying my invention for a stretch of railway track which is provided with a plurality of signals spaced consecutively along the stretch of track for governing traffic movements over the stretch of railway track; which embodies a plurality of polar control relays, one for each given signal location, connected in series, each of the polar control relays having one or more contacts which, when the corresponding relay becomes deenergized, remain closed in the normal or the reverse position to which they were last previously operated in response to current of normal or of reverse polarity, respectively; which also embodies a plurality of neutral line relays, one for each polar control relay, connected in series with the polar control relays; in which a back contact of each of the neutral line relays is included in a path connected in shunting relation around the control winding of the corresponding polar control relay; in which energization of a circuit, including the polar control relays and the neutral line relays connected in series, by current of normal or reverse polarity, is manually controllable from only one control station; in which contacts of traffic controlled relays are included in series with the control windings of the polar control relays and the neutral line relays; in which two track circuits of the coded type are provided for each of given track sections, one for each direction of traffic movements; in which the track circuits for a given direction of traffic movements are set up by contacts of the polar control relays when closed in the given or normal position, and by back contacts of the neutral line relays, and the track circuits for the opposite direction of traffic movements are set up by contacts of the polar control relays when closed in the opposite or reverse position, and by back contacts of the neutral line relays; which also embodies a plurality of line relay repeater relays, one for each of said neutral

line relays controlled by a front contact of the corresponding neutral line relay; in which a front contact of each of the line relay repeater relays is included in multiple with other relay contacts in the traffic locking control circuit; and which also embodies traffic direction stick relays controlled by the line relay repeater relays and the signal relays, for controlling track section or block indication control means.

Similar reference characters refer to similar parts in the drawings.

A stretch of railway track is illustrated, over which traffic movements are normally made from left to right, as shown in the drawings, which I shall assume is the eastbound direction, but over which traffic movements may also at times be made in the opposite or westbound direction. In order to simplify the drawings, the track, comprising two parallel series of track rails, is represented by a single line.

The stretch of track is divided by insulated joints 6 into sections, designated by the reference characters 1T, AT, BT and 5T. Each of the track sections 1T and 5T is provided with a track circuit including a suitable source of current such as a battery 7, connected across the rails adjacent one end of the section, and a track relay designated by the reference character 1TR or 5TR, respectively, connected across the rails adjacent the opposite end of the section.

A suitable source of alternating current is provided such, for example, as an alternator, designated by the reference character L, shown in Fig. 1b, having terminals BX and NX.

Each of the track sections AT and BT is provided with a first track circuit which is at times supplied with coded alternating current adjacent the east end of the corresponding section for controlling eastbound traffic governing means, and is provided with a second track circuit which is at times supplied with coded alternating current adjacent the west end of the corresponding section for controlling westbound traffic governing means. Each of the track circuits for section AT includes the winding d of a track transformer, designated by the reference character 3LT, connected across the rails adjacent the east end of the section, and the winding d of a track transformer, designated by the reference character 2RT, connected across the rails adjacent the west end of the section.

For controlling eastbound traffic governing means, the eastbound track circuit for section AT becomes energized by coded alternating current supplied to winding m of transformer 3LT from terminals BX and NX over front contacts of an eastbound traffic control relay, designated by the reference character 3EFP. A code following direct current track relay, which may be of the biased neutral type operable by only current of the polarity indicated by the arrow in the symbol for the relay, for the eastbound track circuit for section AT, designated by the reference character 2RTR, becomes energized by current received from winding m of transformer 2RT over back contacts of a westbound traffic control relay, designated by the reference character 2WFP, through a rectifier, designated by the reference character 2RI.

For controlling westbound traffic governing means the westbound track circuit for section AT becomes energized by alternating current supplied to winding m of transformer 2RT from terminals BX and NX over front contacts of the westbound traffic control relay 2WFP.

Each of the track circuits for section BT includes the winding d of a track transformer, designated by the reference character 4LT, connected across the rails adjacent the east end of the section, and the winding d of a track transformer, designated by the reference character 3RT, connected across the rails adjacent the west end of the section. The track circuits for section BT become energized similarly to the track circuits for section AT, as already described, for controlling track relays, designated

by the reference characters 3RTR and 4LTR, for controlling eastbound and westbound traffic governing means, respectively.

The rectifiers 2RI, 3RI, 3LI and 4LI may be of any suitable design such, for example, as the well-known bridge type comprising four asymmetric units, designated by the reference characters i1, i2, i3, and i4, which may be of the well-known copper oxide half-wave rectifier type.

10 Signals designated by the reference characters RA2 and L2 are located adjacent the opposite ends of track section 1T, and signals designated by the reference characters R4 and LA4 are located adjacent the opposite ends of track section 5T. A signal designated by the reference character R3 is located adjacent the adjoining ends of sections AT and BT. Signals RA2, R3 and R4 govern eastbound traffic movements, and signals L2 and LA4 govern westbound traffic movements. The signals may be of any suitable design such, for example, as the well-known color light type, each of which has green, yellow and red light units, designated by the reference characters G, Y and R, respectively, as shown in the drawings.

Track switches such as those designated by the reference characters 1 and 5 may be located in track sections 1T and 5T, respectively.

Operation of signals RA2, L2, R4 and LA4 and switches 1 and 5 may be controlled, at least in part, by manually operable devices such, for example, as interlocking machine levers, designated by the reference characters 2V and 4V, for controlling the signals. Each of the levers 2V and 4V has a normal position designated by the reference character n, in which it is shown in the drawings, and also a reverse position designated by the reference character r to the right, as shown in the drawings, and a reverse position designated by the reference character f to the left, as shown in the drawings.

A traffic lever, designated by the reference character FV, is also provided adjacent lever 2V, as shown in Fig. 1a. Lever FV has a normal position n, in which it is shown, and a reverse position r to the right, as shown in the drawing.

Contacts operated by levers 2V, 4V and FV are represented by circles, in each of which is placed a reference character to show the position of the corresponding lever in which the contact is closed. Contact 77 of lever 2V, for example, shown in the upper left-hand corner of Fig. 1a, is represented by a circle in which the reference character r is enclosed to show that contact 77 is closed while lever 2V is in its r position only. As another example, contact 16 of lever 2V, shown just below contact 77, is represented by a circle in which the reference character nf is enclosed to show that contact 16 is closed while lever 2V is in either its n or its f position or at any point between those two positions.

55 Time locking stick relays, designated by the reference characters 2AS and 4AS, are controlled in part by levers 2V and 4V, respectively, in conjunction with the control of signals by these levers.

Time element devices, shown as time element relays designated by the reference characters 2TE and 4TE, are associated with the control of relays 2AS and 4AS, respectively, by levers 2V and 4V, respectively. Each of the time element relays 2TE and 4TE is of a type having contacts which become closed only upon the lapse of a measured period of time after the corresponding relay becomes energized.

A signal lighting relay, designated by the reference character RA2ER, is controlled in part by lever 2V for controlling signal RA2. Signal lighting relays, designated by the reference characters LA4ER and 4RER, are controlled in part by lever 4V for controlling signals LA4 and R4, respectively.

Polar control relays are provided, one for each given signal location. Each of the polar control relays is designated by the reference character F1R preceded by a nu-

meral which is the same as that in the reference character for a corresponding signal.

Neutral line relays are also provided, one for each polar control relay. Each of the neutral line relays is designated by the reference character BPR preceded by a numeral which is the same as that in the reference character for the corresponding polar control relay.

Line relay repeater relays are provided, one for each neutral line relay. Each line relay repeater relay is designated by the reference character BPA preceded by a prefix which is the same as that in the reference character for the corresponding neutral line relay, and is controlled by a front contact of a corresponding neutral line relay.

The polar control relays and the neutral line relays are all connected in series in a traffic control circuit which includes front contacts of track relays 1TR and 5TR and front contacts of time locking stick relays 2AS and 4AS, and at times includes front contacts of home signal relays, designated by the reference character HR preceded by a distinguishing prefix, and front contacts of traffic control relays, each of which is designated by the reference character FP preceded by a distinguishing prefix, and also at times includes front contacts of the line relay repeater relays.

The polar control relays and neutral line relays in the traffic control circuit are energized by current of normal or reverse polarity controlled by a master polar relay, designated by the reference character FSR, which is in turn controlled by pole-changing contacts of traffic lever FV. Under some conditions, the master polar relay FSR could be omitted, and energization of the polar control relays and neutral line relays by current of normal or reverse polarity could then be controlled directly by pole-changing contacts of traffic lever FV.

Each of the polar control relays FR, when energized by current of normal or reverse polarity, controls an eastbound or a westbound traffic control relay, respectively, designated by the reference characters EFP and WFP, respectively, preceded by a distinguishing numeral.

Code transmitting devices, each designated by the reference character CT, preceded by the reference character 75 or 180, may be of a type having a contact which, while the corresponding code transmitting device CT is energized, will open and close at a frequency of 75 or 180 times per minute, respectively. Each of the code transmitting devices CT is connected directly across the terminals of a suitable source of current, and therefore its contact is being repeatedly opened and closed at the frequency of 75 or 180 times per minute, as designated by the reference character of the corresponding device CT.

A decoding transformer, designated by the reference character 2T, has a primary winding *m* which becomes energized by pulses of current of alternately one polarity or the other controlled by relay 2RTR.

A home signal relay, designated by the reference character 2RHR, for signal RA2, is normally deenergized, but becomes energized by current of either the 75 or the 180 code frequency supplied from secondary winding *d* of transformer 2T through a rectifying contact 57 of relay 2RTR. A distant signal relay, designated by the reference character 2RDR, for signal RA2, is normally deenergized, but becomes energized through a decoding unit, designated by the reference character 180DU, which is of a well-known type passing only current of the 180 code frequency. Relay 2RDR will therefore be operated only while winding *m* of transformer 2T is being energized by current of the 180 code frequency.

Decoding transformers, designated by the reference characters 3T and 4T for signals R3 and LA4, respectively, become energized similarly to transformer 2T as just described.

Home and distant signal relays, designated by the reference characters 3RHR and 3RDR, respectively, for signal R3 are operated similarly to relays 2RHR and 2RDR, respectively. Home and distant signal relays,

designated by the reference characters 4LHR and 4LDR, respectively, for signal LA4 are also operated similarly to relays 2RHR and 2RDR, as already described. A home signal relay, designated by the reference character 3LHR, becomes energized in response to operation of relay 3LTR by coded current. Each of the relays 2RHR, 3RHR and 4LHR is of a type which is slow to pick up and slow to release. Relay 3LHR is made slow to release by an asymmetric unit, designated by the reference character *i*5, connected in multiple with its control winding.

A traffic direction stick relay, designated by the reference character BPS preceded by a distinguishing prefix, is provided for each end of each of the track sections AT and BT. Each traffic direction stick relay BPS has a pickup circuit controlled by a front contact of a corresponding line relay repeater relay BPA, and has a stick circuit controlled by a back contact of a home signal relay HR.

A lighting relay, designated by the reference character R3ER for signal R3, is normally energized by a circuit including front contacts of relays 2BPS and 3LBPS, and is also energized when home signal relay 2RHR becomes energized and relay 2BPS becomes deenergized in response to manual control for controlling signal RA2 to display a proceed indication for an eastbound train. When an eastbound train then enters section AT, thereby deenergizing relay 2RHR, relay R3ER becomes deenergized and effects approach lighting of signal R3. Relay R3ER, upon becoming deenergized, also opens an energizing circuit for a block indication relay, designated by the reference character ATPR, for section AT.

When relay 3LHR becomes energized for a westbound traffic movement, relay R3ER becomes energized by a third circuit including a front contact of relay 3LHR and a back contact of relay 3LBPS. Relay 3LHR, upon then becoming deenergized by a westbound train, causes relay R3ER to become deenergized, which opens the energizing circuit for block indication relay ATPR.

A block indication relay, designated by the reference character BTPR for section BT, is controlled, similarly to indication relay ATPR just described, by traffic direction stick relays 3RBPS and 4BPS, and by home signal relays 3RHR and 4LHR for eastbound and westbound traffic movements, respectively.

Block indicators, designated by the reference characters ATBK and BTBK, are controlled by the block indication relays ATPR and BTPR, respectively. As shown in Fig. 1a of the drawings, the block indicators are electric lamps, but they may be of any other suitable type.

A suitable source of current such, for example, as a battery, designated by the reference character 2Q, having terminals designated by the reference characters 2B and 2N, is provided adjacent the west end of the stretch of track, and a suitable source of current such, for example, as a battery, designated by the reference character 4Q, having terminals designated by the reference characters 4B and 4N, is provided adjacent the east end of the stretch of track. A third suitable source of current such, for example, as a battery, designated by the reference character 3Q, having terminals designated by the reference characters 3B and 3N, is provided adjacent signal R3.

Having described, in general, the arrangement and control of the various parts of one form of apparatus embodying my invention, I shall now describe the circuits and operation in detail.

As shown in the drawings, each of the track sections 1T, AT, BT and 5T is unoccupied; relays 1TR and 5TR are energized; each of the levers 2V and 4V is in the normal or *n* position, and therefore each of the signals RA2, L2, R4 and LA4 is displaying the red or stop indication; signal R3 is unlighted; relays 2AS and 4AS are energized; relays 2TE and 4TE are deenergized; traffic control lever FV is in its *n* position, and therefore relay FSR is energized by current of normal polarity; with relay FSR energized by current of normal polarity, its pole-changing contacts

62 and 76 are closed in the normal position for energizing the polar control relays 2FR, 3FR and 4FR, and the neutral line relays 2BPR, 3BPR and 4BPR, by current of normal polarity; relays 2EFP, 3EFP, 4EFP, 2BPA, 3BPA, 4BPA, 2BPS, 3LBPS, 4BPS, R3ER, ATPR and BTPR, and indication devices ATBK and BTBK are therefore also energized; each of the code transmitting devices 75CT and 180CT is constantly energized, and is therefore repeatedly closing and opening its contacts alternately at a frequency of 75 or 180 times per minute, respectively; and relays 2WFP, RA2ER, 3WFP, 3LTR, 2RTR, 3RTR, 2RHR, 3RHR, 2RDR, 3LHR, 3RDR, LA4ER, 4RER, 4LDR, 4LHR, 4LTR, and 4WFP are deenergized.

In Fig. 1a, code transmitting device 75CT is connected directly across terminals 2B and 2N, and is therefore repeatedly closing and opening its contact 87 at a frequency of 75 times per minute. In Fig. 1b, code transmitting devices 75CT and 180CT are connected directly across terminals 3B and 3N, and are therefore repeatedly closing and opening their contacts at a frequency of 75 and 180 times, respectively, per minute. In Fig. 1c, code transmitting devices 75CT and 180CT are connected directly across terminals 4B and 4N, and are therefore repeatedly closing and opening their contacts at a frequency of 75 and 180 times, respectively, per minute.

In Fig. 1a, red lamp R of signal RA2 is shown lighted by a circuit passing from terminal 2B, through the back point of contact 8 of relay RA2ER, and lamp R of signal RA2 to terminal 2N. The red lamps of signals L2, R4 and LA4 are also lighted by circuits which are similar to the circuit just traced for signal RA2.

As shown in Fig. 1a, relay 2AS is energized by a stick circuit passing from terminal 2B, through contact 16 of lever 2V, contact 17 of relay RA2ER, front point of contact 18 of relay 2AS, and the winding of relay 2AS to terminal 2N. Relay 4AS, shown in Fig. 1c, is also energized by a similar stick circuit.

Relay FSR is energized by current of normal polarity passing from terminal 2B, through contact 26 of lever FV, winding of relay FSR, and contact 27 of lever FV to terminal 2N. Relays 2BPR, 2FR, 3BPR, 3FR, 4BPR and 4FR are therefore energized by current of normal polarity in a circuit which will be traced later. The polar contacts of each of the relays 2FR, 3FR and 4FR are therefore closed in the normal position.

With contact 39 of relay 4FR closed in the normal position, relay 4EFP is energized by both a pickup and a stick circuit, the pickup circuit passing from terminal 4B, through contact 30 of relay 4FR closed in the normal position, contacts 31 and 32 of relays 4AS and 5TR, respectively, contact 34 of relay 4WFP, and the winding of relay 4EFP to terminal 4N. The stick circuit for relay 4EFP is the same as the pickup circuit just traced except that it includes contact 33 of relay 4EFP instead of contacts 31 and 32 of relays 4AS and 5TR, respectively.

Relay 3EFP is energized by a stick circuit which passes from terminal 3B, through contact 44 of relay 3FR closed in the normal or left-hand position, as shown in the drawing, contact 46 of relay 3EFP, contact 47 of relay 3WFP, and the winding of relay 3EFP to terminal 3N.

Relay 2EFP is also energized by a stick circuit which passes from terminal 2B, through contact 58 of relay 2FR closed in the normal or left-hand position, contact 60 of relay 2EFP, contact 61 of relay 2WFP, and the winding of relay 2EFP to terminal 2N.

Relay 2BPA is energized by an obvious circuit passing from terminal 2B, through contact 109 of relay 2BPR, and the winding of relay 2BPA to terminal 2N. Each of relays 3BPA and 4BPA is energized by a circuit similar to the circuit just described for relay 2BPA, controlled by contact 100 of relays 3BPR and 4BPR, respectively.

With the track relays 1TR and 5TR, time locking stick relays 2AS and 4AS, eastbound traffic control relay 4EFP, and the line relay repeater relays 2BPA, 3BPA and 4BPA energized while relay FSR is energized by current of nor-

mal polarity, relays 2FR, 3FR, 4FR, 2BPR, 3BPR and 4BPR are energized by current of normal polarity passing from terminal 2B, through contact 62 of relay FSR closed in the normal or left-hand position, as shown in Fig. 1a of the drawings, contacts 63 and 64 of relays 1TR and 2AS, respectively, windings of relays 2BPR and 2FR, contact 102 of relay 2BPA, contact 102 of relay 3BPA, windings of relays 3BPR and 3FR, contact 71 of relay 4EFP in multiple with contact 102 of relay 4BPA, windings of relays 4BPR and 4FR, contacts 74 and 75 of relays 4AS and 5TR, respectively, and contact 76 of relay FSR closed in the normal position, to terminal 2N.

Relays 2EFP, 2WFP, 3EFP, 3WFP, 4EFP, 4WFP, 2BPA, 3BPA and 4BPA are of the slow release type.

The pickup circuit which is closed for relay 2BPS passes from terminal 3B, through contact 103 of relay 2BPA, and the winding of relay 2BPS to terminal 3N. The stick circuit for relay 2BPS passes from terminal 3B, through the back point of contact 107 of relay 2RHR, contact 108 of relay 2BPS, and the winding of relay 2BPS to terminal 3N. The pickup and stick circuits for relay 4BPS are controlled, similarly to the circuits just described for relay 2BPS, by contact 106 of relay 4BPA and the back point of contact 113 of relay 4LHR, respectively.

Relay 3RBPS is also controlled, similarly to relay 2BPS, by pickup and stick circuits controlled by contact 104 of relay 3BPA and the back point of contact 109 of relay 3RHR, respectively. Pickup and stick circuits for relay 3LBPS are closed, which are also similar to the circuits traced for relay 2BPS, and include contact 105 of relay 3BPA and the back point of contact 111 of relay 3LHR, respectively.

Relay R3ER is energized by a circuit passing from terminal 3B, through the front point of contact 115 of relay 2BPS, front point of contact 116 of relay 3LBPS, and the winding of relay R3ER to terminal 3N.

Relay ATPR is energized by a circuit passing from terminal 3B, through contact 117 of relay R3ER, and the winding of relay ATPR to terminal 3N. Relay BTPR is energized by a circuit passing from terminal 4B, through the front point of contact 118 of relay 4BPS, front point of contact 119 of relay 3RBPS, and the winding of relay BTPR to terminal 4N. Track section or block indicators ATBK and BTBK are energized by obvious circuits passing from terminal 2B, through contacts 120 and 121 of relays ATPR and BTPR, respectively, to terminal 2N.

I shall assume that a leverman moves lever 2V to the 'r' position in order to clear signal RA2 for an eastbound train. When lever 2V is moved away from its 'n' position towards its 'r' position, contact 16 of lever 2V will become opened, thereby deenergizing relay 2AS. Upon deenergization of relay 2AS, contact 64 of this relay will open the circuit previously traced for the BPR and FR relays, thereby causing the BPR and FR relays to be deenergized.

With relays 2BPR, 3BPR and 4BPR deenergized, contact 109 of each of these relays will become opened, thereby causing relays 2BPA, 3BPA and 4BPA, respectively, to become deenergized. With relay 4BPA deenergized, the pickup circuit for relay 4BPS which includes contact 106 of relay 4BPA will become opened, but relay 4BPS will then remain energized by its stick circuit, previously described.

With relay 4BPR deenergized, a circuit will be completed for energizing winding *m* of track transformer 4LT by current of 75 code frequency passing from terminal BX, through contact 101 of relay 4BPR, contact 35 of code transmitting device 75CT, back point of contact 37 of relay 4RER, front point of contact 38 of relay 4EFP, winding *m* of transformer 4LT, and the front point of contact 39 of relay 4EFP to terminal NX. Alternating current, coded at the frequency of 75 times per minute, is therefore supplied by winding *d* of transformer

4LT over the rails of section BT to winding *d* of transformer 3RT.

With transformer 3RT thus energized, relay 3RTR is energized by circuit means including winding *m* of transformer 3RT, back point of contact 41 of relay 3WFP, rectifier 3RI, winding of relay 3RTR, and the back point of contact 49 of relay 3WFP. With relay 3RTR thus energized by current coded at the frequency of 75 times per minute, primary winding *m* of transformer 3T is being repeatedly energized by current pulses of normal and reverse polarity alternately. The circuit by which the pulses of normal polarity are supplied to winding *m* of transformer 3T passes from terminal 3B, through the front point of contact 42 of relay 3RTR, and the middle portion of winding *m* of transformer 3T to terminal 3N. The circuit by which the pulses of reverse polarity are supplied to winding *m* of transformer 3T passes from terminal 3B, through the back point of contact 42 of relay 3RTR, and the lowest portion of winding *m* of transformer 3T, as shown in the drawing, to terminal 3N.

Relay 3RHR is therefore energized by current passing from winding *d* of transformer 3T through a rectifying contact 43 of relay 3RTR. With winding *m* of transformer 3T energized by pulses of current of normal and reverse polarities at the frequency of 75 times per minute, relay 3RDR will not be energized, since current of this frequency cannot pass through the corresponding decoding unit 180DU.

With relay 3BPA deenergized, the pickup circuits for relays 3RBPS and 3LBPS are now open at contacts 104 and 105, respectively, of relay 3BPA. Relay 3LBPS, however, remains energized by its stick circuit previously described.

With relay 3RHR now energized, the stick circuit for relay 3RBPS will become opened at the back point of contact 109 of relay 3RHR, so that relay 3RBPS will be deenergized. With relay 3RHR energized and relay 3RBPS deenergized, relay BTPR will be energized by a second circuit, passing from terminal 4B, through the front point of contact 109 of relay 3RHR, back point of contact 119 of relay 3RBPS, and the winding of relay BTPR to terminal 4N.

With relay 3RHR energized, a pickup circuit is now completed for relay 3EFP which is, however, already energized by its stick circuit previously described. The pickup circuit for relay 3EFP is the same as the stick circuit previously described for this relay except that it includes contact 45 of relay 3RHR instead of contact 46 of relay 3EFP.

With relay 3RHR energized while relay 3BPR is deenergized, a circuit is completed for energizing winding *m* of transformer 3LT by alternating current coded at the frequency of 180 times a minute, this circuit passing from terminal BX, through the front point of contact 48 of relay 3EFP, winding *m* of transformer 3LT, front point of contact 49 of relay 3EFP, contact 50 of code transmitting device 180CT, front point of contact 53 of relay 3RHR, and contact 101 of relay 3BPR to terminal NX. Alternating current, code at the frequency of 180 times per minute, is therefore supplied from winding *d* of transformer 3LT over the rails of section AT to winding *d* of transformer 2RT.

Relay 2RTR is therefore energized by a circuit including winding *m* of transformer 2RT, the back point of contact 55 of relay 2WFP, rectifier 2RI, winding of relay 2RTR, and the back point of contact 54 of relay 2WFP. With relay 2RTR thus energized by current coded at the frequency of 180 times per minute, winding *m* of transformer 2T is energized by current of normal and reverse polarity alternately at the frequency of 180 times per minute. Both relays 2RHR and 2RDR are therefore energized.

With relay 2BPA deenergized, the pickup circuit for relay 2BPS is open at contact 103 of relay 2BPA, and with

relay 2RHR energized, the stick circuit for relay 2BPS is open at the back point of contact 107 of relay 2RHR, causing relay 2BPS to now be deenergized. With relay 2RHR energized and relay 2BPS deenergized, a second circuit is completed for relay R3ER, this circuit passing from terminal 3B, through the front point of contact 107 of relay 2RHR, back point of contact 115 of relay 2BPS, front point of contact 116 of relay 3LBPS, and the winding of relay R3ER to terminal 3N.

With relay 2RHR energized, a pickup circuit is completed for relay 2EFP which is, however, already energized by its stick circuit previously traced. The pickup circuit for relay 2EFP is the same as the stick circuit except that it includes contact 59 of relay 2RHR instead of contact 60 of relay 2EFP.

With relay 2RHR energized, a circuit is now completed for energizing relay RA2ER, this circuit passing from terminal 2B, through contact 77 of lever 2V, contacts 78 and 79 of relays 1TR and 2FR, respectively, contact 80 of relay 2RHR, and the winding of relay RA2ER to terminal 2N. With relay RA2ER energized, contact 8 of this relay will become opened, at its back point, thereby extinguishing lamp R of signal RA2, and will become closed at its front point, thereby completing a circuit for lighting green lamp G of signal RA2, this circuit passing from terminal 2B, through the front point of contact 8 of relay RA2ER, front point of contact 9 of relay 2RDR, and lamp G of signal RA2 to terminal 2N.

I shall assume further that, before the eastbound train passes signal RA2, the leverman decides to stop the train at this signal. He will therefore return lever 2V to its *n* position, thereby deenergizing relay RA2ER and thus causing green lamp G of signal RA2 to become extinguished and lamp R of this signal to again be lighted.

With lever 2V again in its *n* position and relay RA2ER deenergized, an energizing circuit will be completed for time element relay 2TE, this circuit passing from terminal 2B, through contact 16 of lever 2V, contact 17 of relay RA2ER, back point of contact 18 of relay 2AS, and relay 2TE to terminal 2N.

Upon the lapse of a measured period of time, relay 2TE will close its front contact 19, thereby completing a pickup circuit for relay 2AS, this circuit passing from terminal 2B, through contact 16 of lever 2V, contact 17 of relay RA2ER, contact 19 of relay 2TE, and the winding of relay 2AS to terminal 2N. Relay 2AS, upon becoming energized by this pickup circuit, will again complete its stick circuit previously traced, and will also complete, at its contact 64, a circuit for energizing the BPR relays.

The circuit now closed for energizing the BPR relays passes from terminal 2B, through contact 62 of relay FSR closed in the normal position, contacts 63 and 64 of relays 1TR and 2AS, respectively, winding of relay 2BPR, contact 65 of relay 2BPR in multiple with the winding of relay 2FR, contact 66 of relay 2RHR, contact 68 of relay 3RHR, winding of relay 3BPR, contact 70 of relay 3BPR in multiple with the winding of relay 3FR, contact 71 of relay 4EFP, winding of relay 4BPR, contact 73 of relay 4BPR in multiple with the winding of relay 4FR, contacts 74 and 75 of relays 4AS and 5TR, respectively, and contact 76 of relay FSR closed in the normal position to terminal 2N. As soon as contacts 65, 70 and 73 of relays 2BPR, 3BPR and 4BPR become opened, relays 2FR, 3FR and 4FR, respectively, will become energized in series with relays 2BPR, 3BPR and 4BPR.

With relays 2BPR, 3BPR and 4BPR again energized, relays 2BPA, 3BPA and 4BPA will in turn also be energized by their circuits previously described. With relays 3BPR and 4BPR again energized, the eastbound track circuits previously traced for sections AT and BT will become deenergized because contact 101 of relays 3BPR and 4BPR will now be open in the energizing circuit for winding *m* of transformers 3LT and 4LT, respectively. Relays 2RHR and 3RHR will therefore also again become deenergized. The BPR and FR relays

will now be energized by their circuits previously traced including contact 102 of each of the relays 2BPA, 3BPA and 4BPA.

I shall assume that the leverman later decides to again clear signal RA2 for the eastbound train. He will therefore again move lever 2V to its *r* position, causing relay 2AS to again become deenergized and therefore again open, at its contact 64, the circuit for the FR and BPR relays. With relays 4BPR and 3BPR again deenergized, the eastbound track circuits for sections BT and AT again become energized as previously described, causing relays 3RHR, 2RHR and 2RDR to again also become energized in turn as previously described. With relay 2RHR again energized, relay RA2ER will also again become energized, and lamp G of signal RA2 will now again be lighted.

When the eastbound train enters section 1T, deenergizing relay 1TR, contact 78 of this relay will open the circuit previously traced for relay RA2ER, causing relay RA2ER to become deenergized. Lamp G of signal RA2 will therefore be extinguished, and lamp R will again be lighted. When relay 1TR becomes deenergized, its contact 63 opens the circuit for the BPR and FR relays at another point.

If, now, while the train is on section 1T, the leverman returns lever 2V to its *n* position, relay 2AS will become energized by a second pickup circuit, this circuit passing from terminal 2B, through contact 16 of lever 2V, contact 17 of relay RA2ER, contact 20 of relay 1TR, and the winding of relay 2AS to terminal 2N. With relay 2AS again energized, its contact 64 will be closed in the circuit for the BPR and FR relays, but this circuit will be open at contact 63 of relay 1TR.

If it is decided to permit the eastbound train to continue its movement past signal R4 at the opposite end of the stretch, a leverman will move lever 4V to its *r* position, thereby completing a circuit for energizing relay 4RER, this circuit passing from terminal 4B, through contact 81 of lever 4V, contact 82 of relay 5TR, and the winding of relay 4RER to terminal 4N. With relay 4RER thus energized, its contact 12 will open the circuit for the red lamp R of signal R4, and, at its front point, will complete a circuit for lighting either lamp Y or lamp G of this signal, according to traffic conditions in advance, as indicated by the dotted portion of the circuits controlled by the front point of contact 12 of relay 4RER.

With relay 4RER energized, alternating current, coded at the frequency of 180 times per minute will be supplied to winding *m* of transformer 4LT over a circuit passing from terminal BX, through contact 101 of relay 4BPR, contact 36 of code transmitting device 180CT, from point of contact 37 of relay 4RER, front point of contact 38 of relay 4EFP, winding *m* of transformer 4LT, and the front point of contact 39 of relay 4EFP to terminal NX. Winding *d* of transformer 4LT will therefore supply alternating current, coded at the frequency of 180 times per minute, to the rails of section BT, for energizing winding *d* of transformer 3RT.

Relay 3RTR will therefore now be energized by current coded at the frequency of 180 times per minute, so that winding *m* of transformer 3T will now be energized by current of normal and reverse polarity alternately at the frequency of 180 times per minutes. Relay 3RHR will therefore be energized as before, and, in addition, relay 3RDR will be energized by current of the 180 code frequency passing through the decoding unit 180DU.

The eastbound train, upon entering section AT, will deenergize winding *d* of transformer 2RT, which in turn will cause relay 2RTR to become deenergized, and then transformer 2T and relays 2RDR and 2RHR will also become deenergized. Relay 2RHR, upon becoming deenergized, opens the pickup circuit for relay 2EFP, which, however, remains energized by its stick circuit.

When relay 2RHR becomes deenergized, its contact 80

opens the circuit for relay RA2ER at another point, and its contact 66 also opens the circuit for relays BPR and FR at another point. With relay 2RHR deenergized, the second circuit traced for relay R3ER will now be opened at the front point of contact 107 of relay 2RHR, causing relay R3ER to be deenergized. When relay R3ER becomes deenergized, its contact 117 will open the circuit previously described for relay ATPR, causing relay ATPR to become deenergized. With relay ATPR deenergized, its contact 126 will open the circuit for block indicator ATBK, causing this indicator to be extinguished.

With relay R3ER deenergized, lamp G of signal R3 will become lighted by a circuit passing from terminal 3B, through contact 122 of relay R3ER, front point of contact 13 of relay 3EFP, front point of contact 14 of relay 3RHR, front point of contact 15 of relay 3RDR, and lamp G of signal R3 to terminal 3N.

When the train leaves section 1T, relay 1TR will become energized, thereby opening its contact 20 in the second pickup circuit traced for relay 2AS. Contact 78 of relay 1TR will now again be closed in the circuit for relay RA2ER, and contact 63 of relay 1TR will again be closed in the circuit for the BPR and FR relays.

When the train enters section BT, winding *d* of transformer 3RT will become deenergized, causing relay 3RTR to become deenergized, and in turn causing transformer 3T and relays 3RHR and 3RDR to also be deenergized. The pickup circuit for relay 3EFP will now be open at contact 45 of relay 3RHR, but relay 3EFP will remain energized by its stick circuit.

When relay 3RHR becomes deenergized, its contact 68 will open the circuit for the BPR and FR relays at another point, and its contact 53 will open, at its front point, the circuit previously traced for energizing winding *m* of transformer 3LT by current coded at the frequency of 180 times per minute. A circuit will now be completed for energizing winding *m* of transformer 3LT by current coded at the frequency of 75 times per minute, this circuit passing from terminal BX, through the front point of contact 48 of relay 3EFP, winding *m* of transformer 3LT, front point of contact 49 of relay 3EFP, contact 51 of code transmitter 75CT, back point of contact 52 of relay 3LHR, back point of contact 53 of relay 3RHR, and contact 101 of relay 3BPR to terminal NX.

When relay 3RHR becomes deenergized, its contact 14 will open, at its front point, the circuit previously traced for lamp G of signal R3, causing this lamp to be extinguished, and will complete a circuit for lighting lamp R of signal R3, this circuit passing from terminal 3B, through contact 122 of relay R3ER, front point of contact 13 of relay 3EFP, back point of contact 14 of relay 3RHR, and lamp R of signal R3 to terminal 3N. Also, when relay 3RHR becomes deenergized, its contact 109 will open, at the front point, the second circuit previously traced for relay BTPR causing relay BTPR to become deenergized and in turn extinguish the indicator BTBK.

When the train leaves section AT, winding *d* of transformer 2RT will become energized by current coded at the frequency of 75 times per minute, causing relay 2RTR to in turn become energized by current coded at this frequency. Relay 2RHR will therefore again be energized, but relay 2RDR will remain deenergized. With relay 2RHR again energized, the pickup circuit for relay 2EFP will again become closed at contact 59 of relay 2RHR. Also, with relay 2RHR again energized, its contact 66 will again be closed in the circuit for relays BPR and FR, and contact 80 of relay 2RHR will again be closed in the circuit traced for relay RA2ER.

On account of relay 2RHR again being energized, relay R3ER will again be energized by the second circuit traced for this relay, thereby extinguishing lamp R of signal R3. With relay R3ER again energized, relay ATPR will also again in turn become energized, and there-

fore lamp ATBK will again become lighted, so that the leverman will know the train has left section AT.

If desired, the leverman can now control signal RA2 to display a yellow or caution indication for a second eastbound train to pass signal RA2. He will accomplish this by again moving lever 2V to the *r* position, thereby causing relay RA2ER to again become energized by its circuit previously traced. With relay RA2ER again energized, while relay 2RDR is deenergized, a circuit will be completed for lighting yellow lamp Y of signal RA2, this circuit passing from terminal 2B, through the front point of contact 8 of relay RA2ER, back point of contact 9 of relay 2RDR, and lamp Y of signal RA2 to terminal 2N.

When the first eastbound train enters section 5T, relay 5TR will become deenergized, causing relay 4RER to become deenergized, and in turn causing lamp G or lamp Y of signal R4 to be extinguished, and lamp R of this signal to again be lighted. Contact 75 of relay 5TR will now be open in the circuit for the BPR and FR relays. The pickup circuit traced for relay 4EFP will be opened at contact 32 of relay 5TR, but relay 4EFP will remain energized by its stick circuit previously traced. With relay 4RER again deenergized, winding *m* of transformer 4LT will be supplied with current coded at the frequency of 75 times per minute, as previously described.

When the first eastbound train leaves section BT, winding *d* of transformer 3RT will again be energized by current coded at the frequency of 75 times per minute, causing relay 3RTR to in turn become energized, so that transformer 3T and relay 3RHR will also be energized, but relay 3RDR will not become energized. With relay 3RHR again energized, relay BTPR will in turn also become energized by its circuit previously traced through the front point of contact 109 of relay 3RHR, and therefore block indicator BTBK will again become lighted. The leverman will thereby be informed that the train has left section BT.

When both eastbound trains have proceeded beyond signal LA4, and lever 2V has again been returned to its *n* position, so that relay 2AS is again energized, relays 2BPR, 3BPR and 4BPR will again become energized by the circuit previously traced through the front contacts of relays 2RHR and 3RHR. The BPR relays, upon becoming energized, will open their back contacts which are connected in multiple with the corresponding FR relays such, for example, as contact 65 of relay 2BPR in multiple with relay 2FR. The BPR relays, upon becoming energized, will also open their back contacts 101 in the energizing circuits for the primary windings of the track transformers for sections AT and BT, thereby deenergizing such track circuits as may have been energized.

The BPR relays upon becoming energized, also close their contacts 100 in the energizing circuits for the BPA relays. The BPA relays, upon becoming energized, complete the pickup circuits for the corresponding traffic direction stick relays BPS, and the energizing circuits first traced for the relays R3ER, ATPR and BTPR are then again closed, and all parts of the apparatus will then again be in the condition shown in the drawings.

I shall next assume that a westbound train is to move over the stretch of track shown in the drawings. A leverman will therefore move lever FV to its *r* position, causing relay FSR to become energized by current of reverse polarity passing from terminal 2B, through contact 28 of lever FV, winding of relay FSR, and contact 29 of lever FV to terminal 2N. Contacts 62 and 76 of relay FSR will therefore be moved to the reverse position. While these contacts are moving from the normal to the reverse position, the BPR and FR relays will become deenergized, and energy will be removed from the BPA relays. If the contacts of relay FSR move quickly enough between their extreme positions, or if the BPA relays are of the slow release type, as shown in the drawings, front contacts of the BPA relays will not become opened because of the brief period of deenergization of the BPR relays during

movement of the contacts 62 and 76 of relay FSR from the normal to the reverse position.

When contacts 62 and 76 of relay FSR reach the reverse position, a circuit will be completed for energizing the BPR relays by current of reverse polarity which is otherwise the same as the circuit previously described including contacts 192 of the BPA relays.

With the BPA relays energized, the BPS relays will be energized by their pickup circuits previously described.

Each of the relays 2FR, 3FR and 4FR, upon becoming energized by current of reverse polarity, will move its polar contacts to the reverse position, thereby de-energizing the EFP relays. A pickup circuit will therefore now be completed for energizing relay 2WFP, this circuit passing from terminal 2B, through contact 58 of relay 2FR closed in the reverse position, contacts 83 and 84 of relays 2AS and 1TR, respectively, contact 85 of relay 2EFP, and the winding of relay 2WFP to terminal 2N. Relay 2WFP, upon becoming energized by its pickup circuit, will complete its stick circuit, which is the same as the pickup circuit just traced except that it includes contact 86 of relay 2WFP instead of contacts 83 and 84 of relays 2AS and 1TR, respectively.

A leverman will then move lever 4V to the *f* position to initiate the clearing of signal LA4 for a westbound traffic movement. Lever 4V, upon being moved away from the *n* position toward the *f* position, will open its contact 21, thereby deenergizing relay 4AS. Contact 74 of relay 4AS will then open the circuit for the BPR and FR relays, causing these relays to become deenergized, and causing the BPA relays to also in turn become deenergized and open the pickup circuits for the BPS relays which will, however, remain energized by their stick circuits.

With relay 2BPR deenergized and relay 2WFP energized, winding *m* of transformer 2RT will be energized by current coded at the frequency of 75 times per minute supplied to a circuit passing from terminal BX, through contact 101 of relay 2BPR, contact 87 of code transmitting device 75CT, front point of contact 54 of relay 2WFP, winding *m* of transformer 2RT, and the front point of contact 55 of relay 2WFP to terminal NX. Winding *d* of transformer 3LT will therefore now be energized by current coded at the frequency of 75 times per minute and supplied over the rails of section AT from winding *d* of transformer 2RT.

A circuit will now be completed for energizing relay 3LTR from winding *m* of transformer 3LT, this circuit including winding *m* of transformer 3LT, back point of contact 49 of relay 3EFP, rectifier 3LI, winding of relay 3LTR, and the back point of contact 48 of relay 3EFP. Relay 3LTR will therefore now be periodically energized at a frequency of 75 times per minute, causing contact 88 of relay 3LTR to be closed at its front and back points alternately.

Each time when contact 88 of relay 3LTR becomes closed at its back point, a circuit will be completed for charging an energy storing device, designated by the reference character *e*, this circuit passing from terminal 3B, through the back point of contact 88 of relay 3LTR, energy storing device *e*, and a resistor *t* to terminal 3N. Each time when contact 88 of relay 3LTR becomes closed at its front point, the energy storing device *e* will discharge through the winding of relay 3LHR, by a circuit passing from device *e*, through the front point of contact 88 of relay 3LTR, winding of relay 3LHR, and resistor *t* back to device *e*. Relay 3LHR is made slow releasing by asymmetric unit *i5* connected in multiple with its control winding, and therefore its front contacts 52, 69, 89, and 111 will remain closed while contact 88 of relay 3LTR is being closed alternately at its front and back points.

Relay 3LHR, upon becoming energized, opens the stick circuit for relay 3LBPS, causing relay 3LBPS to be deenergized. Relay R3ER will therefore now be energized by a third circuit, passing from terminal 3B, through

the front point of contact 111 of relay 3LHR, back point of contact 116 of relay 3LBPS, and the winding of relay R3ER to terminal 3N.

A pickup circuit will be completed for relay 3WFP, passing from terminal 3B, through contact 44 of relay 3FR closed in the reverse position, contact 89 of relay 3LHR, contact 91 of relay 3EFP, and the winding of relay 3WFP to terminal 3N. Relay 3WFP, upon becoming energized, will complete its stick circuit, which is the same as the pickup circuit just traced except that it includes contact 90 of relay 3WFP instead of contact 89 of relay 3LHR.

A circuit will now be completed for energizing winding *m* of transformer 3RT by current coded at the frequency of 180 times per minute, this circuit passing from terminal BX, through the front point of contact 40 of relay 3WFP, winding *m* of transformer 3RT, front point of contact 41 of relay 3WFP, contact 50 of code transmitting device 180CT, front point of contact 52 of relay 3LHR, back point of contact 53 of relay 3RHR, and contact 101 of relay 3BPR, to terminal NX. Current coded at the frequency of 180 times per minute will therefore be supplied from winding *d* of transformer 3RT over the rails of section BT, to winding *d* of transformer 4LT.

Relay 4LTR will now be energized by current coded at the frequency of 180 times per minute in a circuit which includes winding *m* of transformer 4LT, back point of contact 39 of relay 4EFP, rectifier 4LI, winding of relay 4LTR, and the back point of contact 38 of relay 4EFP. Transformer 4T and relays 4LHR and 4LDR will therefore be energized through contacts 92 and 93 of relay 4LTR while being repeatedly closed at their front and back points alternately at the frequency of 180 times per minute. Relay 4LHR, upon becoming energized, opens the stick circuit for relay 4BPS, causing relay 4BPS to be deenergized, and completes a third circuit for energizing relay BTPR, this circuit passing from terminal 4B, through the front point of contact 113 of relay 4LHR, back point of contact 118 of relay 4BPS, front point of contact 119 of relay 3RBPS, and the winding of relay BTPR to terminal 4N.

With relay 4LHR energized, a pickup circuit will be completed for relay 4WFP, this circuit passing from terminal 4B, through contact 39 of relay 4FR closed in the reverse position, contact 94 of relay 4LHR, contact 96 of relay 4EFP, and the winding of relay 4WFP to terminal 4N. Relay 4WFP, upon becoming energized by its pickup circuit, will complete its stick circuit, which is the same as the pickup circuit just traced except that it includes contact 95 of relay 4WFP instead of contact 94 of relay 4LHR. Signal LA4 will now be controlled to display a green or clear proceed indication for a westbound traffic movement similarly to the manner previously described in which lamp G of signal RA2 was controlled to display a green or clear proceed indication for an eastbound train.

A westbound train, upon now entering section BT, will deenergize winding *d* of transformer 4LT, thereby causing relays 4LTR, 4LHR and 4LDR to be deenergized. The green lamp G of signal LA4 will therefore be extinguished, and the red lamp R will again be lighted. With relay 4LHR deenergized, the third circuit traced for relay BTPR will be open at the front point of contact 113 of relay 4LHR, so that relay BTPR will be deenergized and the indicator BTBK will become extinguished. The leverman will then know that the train has entered section BT.

When the westbound train enters section AT, winding *d* of transformer 3LT will become deenergized, so that relays 3LTR and 3LHR will become deenergized in turn. When relay 3LHR becomes deenergized, the third circuit traced for relay R3ER will become opened at the front point of contact 111 of relay 3LHR, so that relay R3ER will be deenergized. Lamp R of signal R3 will therefore be lighted by a circuit passing from terminal

3B, through contact 122 of relay R3ER, back point of contact 13 of relay 3EFP, and lamp R of signal R3 to terminal 3N. Also, with relay R3ER deenergized, relay ATPR will be deenergized because contact 117 of relay R3ER will be open, and indicator ATBK will therefore be extinguished.

It is believed that, in view of the description of the operation of the apparatus that has been given for the movement of an eastbound train, the operation of the apparatus as the westbound train proceeds further will be readily understood without further detailed description.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In railway traffic controlling apparatus embodying traffic governing means for a given stretch of railway track for governing traffic movements in a first direction and in the opposite or second direction over said stretch of track, embodying a plurality of polar control relays and a plurality of neutral line relays one for each of said polar control relays connected in series in a traffic control circuit, each of said polar control relays having polar contacts which when the corresponding relay becomes deenergized remain closed in a normal or a reverse position to which they were last operated in response to current of normal or reverse polarity respectively, in which energization of said traffic control circuit including said polar control relays and said neutral relays by current of normal and reverse polarities is manually controllable, embodying traffic responsive means energizable while said stretch of track is unoccupied but becoming deenergized in response to occupation of said stretch of track by a railway vehicle, first manual means, second manual means, means controlled by operation of said first or second manual means for initiating the control of said traffic governing means for directing traffic movements onto said stretch of track in said first or said second direction respectively and for deenergizing said neutral line relays, means controlled by said neutral line relays in the deenergized condition and by normal and reverse polar contacts of said polar control relays for effecting energization of said traffic responsive means for traffic movements in said first and second directions respectively, the combination comprising, a line relay repeater relay for each of said neutral line relays each controlled by a front contact of the corresponding neutral line relay, a first traffic direction stick relay and a second traffic direction stick relay each having a pickup circuit controlled by a front contact of a corresponding line relay repeater relay, a stick circuit for said first traffic direction stick relay controlled by said traffic responsive means for said first direction in the deenergized condition, a stick circuit for said second traffic direction stick relay controlled by said traffic responsive means for said second direction in the deenergized condition, traffic indication means, a first circuit controlled by front contacts of said first and second traffic direction stick relays in series for energizing said traffic indication means, a second circuit controlled by said traffic responsive means for said first direction in the energized condition and by a back contact of said first traffic direction stick relay for energizing said traffic indication means, and a third circuit controlled by said traffic responsive means for said second direction in the energized condition and by a back contact of said second traffic direction stick relay for energizing said traffic indication means.
2. In railway traffic controlling apparatus embodying traffic governing means for a given stretch of railway track for governing traffic movements in a first direction and in the opposite or second direction over said stretch of track, embodying a plurality of polar control relays

3. In railway traffic controlling apparatus embodying traffic governing means for a given stretch of railway track for governing traffic movements in a first direction and in the opposite or second direction over said stretch of track, embodying a plurality of polar control relays

and a plurality of neutral line relays one for each of said polar control relays connected in series in a traffic control circuit, each of said polar control relays having polar contacts which when the corresponding relay becomes deenergized remain closed in a normal or a reverse position to which they were last operated in response to current of normal or reverse polarity respectively, in which energization of said traffic control circuit including said polar control relays and said neutral relays by current of normal and reverse polarities is manually controllable, first manual means, second manual means, means controlled by operation of said first or said second manual means for initiating the control of said traffic governing means for directing traffic movements onto said stretch of track in said first or said second direction respectively and for deenergizing said neutral line relays, a first home signal relay, a second home signal relay, means including a normal polar contact of a corresponding polar control relay for energizing said first home signal relay if said stretch of track is unoccupied, means including a reverse polar contact of a corresponding polar control relay for energizing said second home signal relay if said stretch of track is unoccupied, the combination comprising, a line relay repeater relay for each of said neutral line relays each controlled by a front contact of the corresponding neutral line relay, a first traffic direction stick relay and a second traffic direction stick relay each having a pickup circuit controlled by a front contact of a corresponding line relay repeater relay, a stick circuit for said first traffic direction stick relay controlled by said first home signal relay in the deenergized condition, a stick circuit for said second traffic direction stick relay controlled by said second home signal relay in the deenergized condition, traffic indication means, a first circuit controlled by front contacts of said first and second traffic direction stick relays in series for energizing said traffic indication means, a second circuit controlled by said first home signal relay in the energized condition and by said first traffic direction stick relay in the deenergized condition for energizing said traffic indication means, and a third circuit controlled by said second home signal relay in the energized condition and by said second traffic direction stick relay in the deenergized condition for energizing said traffic indication means.

3. In railway traffic controlling apparatus embodying traffic governing means for a given stretch of railway track, including a plurality of polar traffic control relays connected in series in a normally energized traffic control circuit, each of said polar traffic control relays having polar contacts which when the corresponding relay becomes deenergized remain closed in a normal or a reverse position to which they were last operated, manually controllable means for energizing said traffic control circuit by current of normal and reverse polarities, first and second manual control means operable for deenergizing said traffic control circuit arrangement and for initiating operation of said traffic governing means for directing traffic movements in a first and a second or opposite direction respectively over said stretch of railway track, traffic responsive means energizable while said stretch of track is unoccupied but becoming deenergized in response to occupancy of said stretch of track by a railway vehicle, the combination comprising, a first and a second traffic direction stick relay for traffic movements in a first and a second direction respectively over said stretch of track, each of said traffic direction stick relays having a pickup circuit controlled to be closed while said traffic control circuit is energized by current of either normal or reverse polarity, control means for said traffic governing means for said first direction controlled by said traffic responsive means in the energized condition and by a normal polar contact of a corresponding polar traffic control relay, control means for said traffic governing means for said second

direction controlled by said traffic responsive means in the energized condition and by a reverse polar contact of a corresponding polar traffic control relay, a stick circuit for said first traffic direction stick relay controlled by said control means for said traffic governing means for said first direction in the deenergized condition, a stick circuit for said second traffic direction stick relay controlled by said control means for said traffic governing means for said second direction in the deenergized condition, traffic indication means, a first circuit for energizing said traffic indication means controlled by front contacts of said first and second traffic direction stick relays, a second circuit for energizing said traffic indication means controlled by a back contact of said first traffic direction stick relay and by said control means for said traffic governing means for said first direction in the energized condition, and a third circuit for energizing said traffic indication means controlled by a back contact of said second traffic direction stick relay and by said control means for said traffic governing means for said second direction in the energized condition.

4. In railway traffic controlling apparatus embodying traffic governing means for a given stretch of railway track, including a plurality of polar traffic control relays connected in series in a normally energized traffic control circuit, each of said polar traffic control relays having polar contacts which when the corresponding relay becomes deenergized remain closed in a normal or a reverse position to which they were last operated, manually controllable means for energizing said traffic control circuit by current of normal and reverse polarities, first and second manual control means operable for deenergizing said traffic control circuit and for initiating operation of said traffic governing means for directing traffic movements in a first and a second or opposite direction respectively over said stretch of railway track, traffic responsive means energizable while said stretch or track is unoccupied but becoming deenergized in response to occupancy of said stretch of track by a railway vehicle, means controlled by said traffic control circuit in the deenergized condition and by normal and reverse polar contacts of said polar traffic control relays for energizing said traffic responsive means for controlling said traffic governing means for directing traffic movements in said first and second direction respectively, the combination comprising, a first and a second traffic direction stick relay for said first and second directions respectively of traffic movements, each of said traffic direction stick relays having a pickup circuit controlled to be closed in response to energization of said traffic control circuit by current of either normal or reverse polarity, a stick circuit for said first traffic direction stick relay controlled to be closed in response to deenergization of said traffic responsive means for said first direction, a stick circuit for said second traffic direction stick relay controlled to be closed in response to deenergization of said traffic responsive means for said second direction, traffic indication means, and means controlled by front contacts of both of said traffic direction stick relays, or by a back contact of said first traffic direction stick relay while said traffic responsive means for said first direction is energized, or by a back contact of said second traffic direction stick relay while said traffic responsive means for said second direction is energized.

5. In combination, a section of railway track, traffic governing means for governing traffic movements in a first or given direction and in a second or opposite direction over said section, a polar control relay for each end of said section each having polar contacts which when the corresponding relay becomes deenergized remain closed in a normal or a reverse position to which they were last operated, a neutral line relay for each of said polar control relays, traffic responsive means including two track circuits one for each direction of traffic movements over said track section, a traffic control circuit including said

polar control relays and said neutral line relays all in series, manually controllable means for effecting energization of said traffic control circuit by current of normal and reverse polarities, manual means operable for initiating control of said traffic governing means for said first direction and for said second direction and effecting de-energization of said traffic control circuit, means controlled by said neutral line relays in the deenergized condition and by normal and reverse polar contacts of said polar control relays for effecting energization of said track circuits for said first and second direction respectively, a first and a second traffic direction stick relay each having a pickup circuit controlled by a front contact of a corresponding said neutral line relay, a stick circuit for said first traffic direction stick relay controlled by said first track circuit in the deenergized condition, a stick circuit for said second traffic direction stick relay controlled by said second track circuit in the deenergized condition, traffic indication means, and means controlled by front contacts of both of said traffic direction stick relays or by a back contact of said first traffic direction stick relay while said first track circuit is energized or by a back contact of said second traffic direction stick relay while said second track circuit is energized for energizing said traffic indication means.

6. In combination, a section of railway track, traffic governing means for governing traffic movements in a first or given direction and in a second or opposite direction over said section, a polar control relay for each end of said section each having polar contacts which when the corresponding relay becomes deenergized remain closed in a normal or a reverse position to which they were last operated, a traffic control circuit including said polar traffic control relays connected in series, manually controllable means for normally energizing said traffic con-

trol circuit by current of normal or reverse polarity, manual control means operable for initiating operation of said traffic governing means and for deenergizing said traffic control circuit, traffic responsive means for said section energizable while said track section is unoccupied but becoming deenergized in response to occupancy of said section by a railway vehicle, means controlled by said traffic control circuit in the deenergized condition and by normal and reverse polar contacts of said polar traffic control relays for energizing said traffic responsive means for governing said traffic governing means for traffic movements in said first and second directions respectively, a first and a second traffic direction stick relay, a pickup circuit for each of said traffic direction stick relays each controlled to be energized while said traffic control circuit is energized, a stick circuit for said first traffic direction stick relay controlled by said traffic responsive means when deenergized for traffic movements in said first direction, a stick circuit for said second traffic direction stick relay controlled by said traffic responsive means in the deenergized condition for traffic movements in said second direction, traffic indication means, and means controlled by front contacts of both said traffic direction stick relays, or by a back contact of said first traffic direction stick relay while said traffic responsive means is energized for said second direction of traffic movements.
